(57) **CLAIM**

The ornamental design for an applicator tool, as shown and described.

DESCRIPTION

FIG. 1 is a perspective view of an applicator tool showing the new design with the rotatable applicator head shown in a vertical position;

FIG. 2 is a front view thereof;

FIG. 3 is a side view thereof, the opposite side being a mirror image;

FIG. 4 is a rear view thereof;

FIG. 5 is a top view thereof;

FIG. 6 is a bottom view thereof; and,

FIG. 7 is another perspective view thereof with the rotatable applicator head shown in a horizontal position.

The broken line showing of a button is included for illustrative purposes only and forms no part of the claimed design.
